CABLE HOLDER WITH GUIDE SLOTS

Ernest E. Haussler, Clifton, N. J.; Elsie K. Haussler administratrix of said Ernest E. Haussler, deceased

Application January 21, 1949, Serial No. 71,807

1 Claim. (Cl. 81—5.1)

1

This invention relates to tools which are equipped to be used for various but related purposes, such as compound tools, and particularly to an electrician's combined hand vise, wire cutter and stripper and pliers.

The main object of my invention is to provide means in a single tool for performing a group of related functions or operations in connection with the cutting of armored cable and cutting the conductors thereof.

Another object is to have a combined plier-type tool of the indicated character which includes means either for facilitating or actually performing any one of a plurality of operations necessary in cutting an armored cable and preparing the conductors thereof for connection with terminals on electrical apparatus.

A further object is to provide such a combined tool with only one pair of cooperating handles, but in addition to its other facilities, with special gripping means for holding the armored cable fixed while sawing it, and having guide and clearance portions for entry of a saw blade in selected positions for cutting the armor of the cable at will.

It is also an object to have a combined tool for electrical workers which includes two tool elements pivotally connected together by a pivot having wide heads to insure accurate fit of the parts, durable association thereof and elimination of wobbling of the parts.

Other objects and advantages of the invention will appear in further detail as the specification proceeds.

In order to facilitate ready comprehension of this invention for a proper appreciation of the salient features thereof, the invention is illustrated on the accompanying drawing forming part hereof, and in which:

Figure 1 is a top plan view of an electrician's compound tool made according to the invention and embodying the same in a practical form;

Figure 2 is a side elevation of the same electrician's compound tool, as seen from below in Figure 1;

Figure 3 is another elevation of the tool, as seen from the opposite side than that shown in Figure 2;

Figure 4 is an end elevation, as seen from the right in Figure 2.

In the views, the same reference numerals indicate the same or like parts.

Electricians frequently find it necessary to cut armored cables and make connections with conductors of the same, this first necessitating the

2

cutting and/or breaking of the armor sheath of the cable, then cutting the conductors after removing cut portions of armor, and stripping the insulation from the conductors to expose the metal wires of the latter. For this work, several tools are usually employed and even considered necessary, first a vise to hold the cable while being sawed or cut, and then pliers and cutters for removing the cut armor and cutting and stripping the conductors, several tools being thus used in succession, and all too often the vise is not portable and some makeshift is employed instead.

Upon considering this problem, it has occurred to me that facilities could well be combined in a manually-operated tool for performing the various operations, or at least cooperate therewith when required to effect the cutting of an armored cable and exposing the conductors thereof preparatory to connecting the latter to electrical devices and apparatus. As a result, I have succeeded in producing a combined tool as outlined which will now be more fully described.

Hence, in the practice of my invention, and referring again to the drawing, the tool, generally indicated at 5, primarily includes a pair of handles 6 and 7 having corresponding opposite cut-away portions 8 and 9 providing an intermediate cleavage or meeting plane along which the two opposed intermediate tool portions 10 and 11 meet and through which latter portions a pivot bolt 12 extends. The latter has a very large flat head 13 upon one end and upon the other end is screwed a correspondingly large flat nut 14. Rearwardly of the flat cut-out portion 8 handle 6 is provided with an upwardly-extending lug 15 forming a finger stop to prevent the fingers from slipping inwardly into the pivoted portions of the tool and suffering injury, the handle 6 being in addition knurled, as indicated at 16, and preferably the other handle 7 is similarly knurled, and at the free end thereof terminates in a screw driver bit 17. This latter feature serves for unscrewing terminal screws and then tightening them when wires have been connected thereto. Above the pivot bolt 12 extend a pair of opposed jaws 18, 19 which below the upper ends thereof have the arcuate clearance portions 20, 21, these jaws being integral with the tool portions 10 and 11, respectively, and at 22 having a slight clearance between them even in closed position, for a purpose which will presently be described. Thus far described, the tool virtually forms a pair of angle pliers in which the jaws 18 and 19 may be opened or closed by

manipulating handles 6 and 7 about pivot bolt 12.

Forwardly of the pivot bolt, the two flat tool portions 10 and 11 which may be more or less conventional in form, are widened to form a pair of wide jaws 23, 24 which at their innermost portions are formed with mutually-meeting cutting edges 25, 26 toward one end of which they are formed with opposite and corresponding notches 27, 28, 29 and 30 adapted to receive two sizes of wire, for example, members 14 and 16, for stripping insulation therefrom, while the remaining portions of the cutters 25 and 26 are virtually straight and are adapted to meet in actual contact even when the upper jaws 18 and 19 have a clearance 22 therebetween to ensure the meeting of the cutting edges mentioned.

In addition, upon both jaws 23 and 24 are formed spaced pairs of internally-arcuate gripping jaw members 31, 32 on jaw 23 and 33 and 34 on jaw 24, being disposed with the intermediate clearance spaces 36 and 37 between the pairs. Within the cutters 25 and 26 is a clearance portion 38 to facilitate the use of the tool as a plier and a cutter as far as described independently of the presence of the forwardly-projecting and spaced pairs of jaw members 31, 32, 33, 34 already alluded to. Preferably, the inner arcuate portions 39 and 40 of jaw members 31 and 32 on the one hand and members 33 and 34 on the other hand are fluted or serrated to provide an effective grip on the armor of a cable when the same is to be held for sawing portions thereof. In contrast, the outer opposed ends 41, 42, 43, 44 of the jaw members 31 to 34 are spaced a distance apart to provide ample clearance for insertion of an armored cable when the tool is partly opened and to allow the jaw members to be gripped upon the cable with a firm hold preventing any slipping thereof when the cable is being cut or sawed.

For the purpose of facilitating the sawing operation, the jaw members are individually formed with oblique guide slots 45, 46, 47 and 48 arranged in such fashion that slots 45 and 48 are in line and slots 46 and 47 mutually arranged in line, the lines of these slots crossing each other substantially centrally of the length of the cutting edges 25 and 26 and preferably being disposed at 37-degree angles with the mentioned cutting edges. Naturally, any other angle selected might also be used, but the angles mentioned are substantially at right angles to the pitch of the formed metal strips that constitute the armor on the armored cable. The arrangement is such that when an armored cable is gripped between the jaw members, a hack saw may be inserted in slots 45 and 48, or in slots 46 and 47, while the tool 5 is firmly held until the sheath has been sawed through in at least two spaced positions. Thereafter, the tool is used by applying the jaws 18 and 19 forming the plier portion to free the cable from the sawed portions of the sheath and thereafter the cutters 25 and 26 will serve to cut through the insulation and

the wires of the conductors of the cable. Subsequently, each conductor individually is freed of its insulation by applying either the apertured portions 27, 28 or 29 and 30 thereto according to the size of the conductor wire and the insulation stripped from the conductor by pulling the tool toward the cut end of each conductor.

Manifestly, variations may be resorted to and parts and features may be modified or used without others within the scope of the appended claim.

Having now fully described my invention, I claim:

A supporting tool for severing the armor from an armored cable comprising a pair of handles arranged in face to face relation and pivotally connected together adjacent one end thereof for movement toward and away from each other, a first jaw arranged transversely of one of said handles adjacent said one end thereof and having one end fixedly secured to the latter, a first pair of spaced jaw members arranged longitudinally of said first jaw adjacent the other end thereof and each having one end integral with said first jaw, a second jaw arranged transversely of the other of said handles adjacent said one end thereof and having one end fixedly secured to the latter, a second pair of spaced jaw members arranged longitudinally of said second jaw adjacent the other end thereof and each having one end integral with said second jaw, each of the jaw members of said first pair being in spaced facing relation with respect to each of the jaw members of said second pair, there being a slot extending longitudinally through the other end of each of said jaw members and terminating at a point spaced from said one end of the associated jaw member, the slots in each pair of jaw members being at an angle with respect to each other, the slot of each jaw member being in alignment with the slot of the non-facing jaw member of the other pair and forming with the latter a guideway for a cutting blade.
